Athenaeum.

UNITED STATES PATENT OFFICE.

ROBERT S. PHILIP, OF LOS ANGELES, CALIFORNIA.

INKING MECHANISM FOR PRINTING-PRESSES.

1,379,649.

Specification of Letters Patent.

Patented May 31, 1921.

Application filed April 26, 1919, Serial No. 294,002. Renewed April 16, 1921. Serial No. 461,918.

To all whom it may concern:

Be it known that I, ROBERT S. PHILIP, a citizen of the United States, residing in the city of Los Angeles, county of Los Angeles, 5 and State of California, have invented certain new and useful Improvements in Inking Mechanism for Printing-PresSES, of which the following is a specification.

My invention relates to inking mechanism 10 for printing presses, and the primary object thereof is to provide an improved form of distributing means by means of which the ink is delivered in a uniform amount from the inking fountain to the form and in order 15 to carry out the said object, I have provided a new and novel arrangement of old elements, together with certain new elements of my invention, whereby greater speed of the press may be obtained than with other 20 well known types of mechanism.

A further object is to provide in lieu of the generally used disk, to which the ink is transferred from the inking fountain or other ink holding means to the form rollers, 25 a cylinder of large diameter for receiving the supply of ink and from the ink is intermittently transferred to the said form rollers.

Another object is to provide a unit mechanism comprising a suitable frame with a cylinder, distributing rollers, a vibrator roller, and an ink fountain mounted thereon for coöperation and attachable to all types of small presses to which a mechanism of this 35 character is adaptable.

A still further object is to provide independent means for operating the distributing rollers and cylinder and supported on the same frame which holds said rollers, thus 40 providing a separately controlled source of power for the inking mechanism, whereby the inking unit may be readily attached to many common types of presses without alteration of the press or modification of the inking 45 mechanism to suit varying conditions. Other objects will appear as the description progresses.

Having in mind the above and other objects, I have shown in the accompanying 50 drawing, forming a part of this application, a novel arrangement and form of parts com-

bined to provide one practical embodiment of my invention, which I will describe in detail.

Referring to the said drawings, in which 55 similar characters of reference are employed throughout the several views for indicating the same and like parts,

Figure 1 is a plan of my improved mechanism,

Fig. 2 is a side elevation of the same,
Fig. 3 is a rear elevation of the same.

Fig. 4 is a longitudinal section of the same showing the relative positions and size of the various rollers and elements.

Only a portion of a well known type of printing press is shown in the drawings for the purpose of illustrating the manner in which my device may be attached to the frame of the press, the portion so shown 70 being known as the bed of the press, as indicated at 1, and comprising a pair of oppositely positioned members of like character, pivoted to the base of the main frame. Members 1, 1, are adapted to carry the form (not 75 shown) on the front side thereof and are connected near their upper extremities by means of a transverse shaft 2, carried in bearings 3, 3, connecting rods 4, 4, being eccentrically connected with the ends 5, 5, of 80 said shaft and being adapted to connect at their other ends with cranks or eccentrics for moving the back forward and backward during the printing operation.

A form roller bearer 6, is provided on the 85 outer side of each of the back members 1, 1, and is pivoted on the ends of shaft 2, said members being connected at the rear by means of a transverse rail 7. Members 6, 6, are adapted to be oscillated about their common axis and carry on their forward ends a triplet of form rollers *f*, *f*, *f*, which are yieldably supported thereon and are adapted to be moved over the runner faces 8, 8, of the back members 1, 1, in the usual manner, said 90 faces being so arranged as to move the said form rollers backward and forward over the form and in contact with the inking rollers to be hereinafter described, alternately.

My mechanism includes a pair of like frame members 9, 9, provided with teeth 10,

10, on the bottoms thereof which are adapted to rest on and to be attached to the upper portion of members 1, 1, by means of bolts 11, 11. The upper edges 12, 12, of members 9, 9, 5 constitute runner faces for the form rollers *f*, *f*, *f*, and are adapted to form continuations of the runner faces 8, 8, in an inclined plane from the front of the back 1, and the rear ends of said runner faces are substantially 10 horizontal.

Frame members 9, 9, are spaced apart and connected by means of square rods 13, 13, which are held thereon by means of nuts 14, 14, on the outside of said members. Between 15 the members 9, 9, and spaced therefrom at the ends, I provide a metal cylinder C, of substantially large diameter, which is revolvably held on a transverse shaft 15, carried in bearings 16, 16, in frame members 20 9, 9, and the runner faces of frames 9, 9, at the rear ends are slightly lower than the periphery of said cylinder, as shown.

An electric motor M is supported on a plate 17, which is suspended from the transverse spacer rods 13, 13, and attached thereto and motion is adapted to be communicated to the cylinder C from motor M by means of a train of speed reduction gears including a pinion 18, on the motor shaft 19, 25 an idler set of gears 20 and 21 of different size on a stud or shaft 22, attached to one end of the frame members 9, an idler 23 on a stud or shaft 25 also attached to frame 9, and a relatively larger gear 26 carried on 30 the cylinder shaft 15. Thus pinion 18 drives gears 20 and 21, gear 21 drives gear 23, and gear 23 drives the cylinder gear 26, and the cylinder C is rotated continuously in a clockwise direction during the operation of the 40 press.

A pair of composition distribution rollers *d* and *d'* are carried on shafts 27 and 28, respectively, between the frame members 9, 9, and the ends of said shafts are loosely held 45 in inclined slots 29 and 30, formed in the rear edges of said frame members, so that the rollers *d* and *d'* will contact loosely with the large cylinder C. The slots 30, 30, in frame members 9, 9, are so disposed as to 50 also hold the flattened ends 31, 31, of a transverse screw 32, having right and left intersecting threads thereon and a vibrator roller V, is supported on said screw so as to contact with both of the distributing rollers 55 *d* and *d'*, and is rotated thereby, thus causing a longitudinal movement of the roller on the screw, as in other types of vibrator rollers, for providing a uniform distribution 60 of the ink on rollers *d* and *d'*.

60 The ink fountain F comprises a housing 33 having feet 34, 34, thereon adapted to be attached to lugs 35, 35, formed on the rear sides of the frames 9, 9, and a metal roller 1, which is carried in separable bearings 36, 65 36, at the ends of said housing. Fountain

F has the usual thin metallic contact plate 37 in the bottom thereof, which is adapted to be pressed against the periphery of ink roller *i*, by means of a plurality of thumb screws, 39, 39, etc., for regulating the quantity of ink delivered from the ink roller *i* to the other rollers.

Intermediate of ink roller *i*, and the vibrator roller V, I provide a ductor roller D, of composition material, which is pivotally mounted on arms 40, 40, at the ends and is adapted to intermittently contact with the roller *i* and roller V for delivering a quantity of the ink to the distributing rollers. Arms 40 and 40' are pivoted on a transverse 80 rod 41 attached at the ends to the frame members 9, 9.

The inking roller *i*, is operated in the usual manner by means of a ratchet 41, carried on the end of said roller and a pawl 42 carried on an arm 43 and pivoted on the end of roller *i*, a rod 44, being attached to the end of the arm 43, which is adapted to be actuated by and at each oscillation of the form roller bearer members, 6, 6. The ductor roller D is oscillated between the rollers *i* and V, by means of an extension 45, on arm 40, projecting into the path of member 7 of the form roller bearer 6, and is adapted to be engaged thereby at each operation for engaging rollers D and V. Extension 45 may have a weight 46 thereon for restoring roller D to contact with roller *i* after each operation.

What I claim is:

1. In a printing press, the combination with the movable bed and form rollers supported thereon, of extensions carried on said bed, an inking cylinder rotatably held between and on said extensions, a driving element supported on said extensions, a reduction gearing train operably connecting said driving element with said cylinder, distributing rollers movably engaging the periphery of said cylinder, a vibrator roller movably engaging said distributing rollers, an inking mechanism including a roller for supplying ink to said vibrator roller, and a ductor roller movably disposed intermediate said inking roller and said vibrator roller.

2. In a printing press, the combination with the movable bed and form rollers supported thereon, of extensions carried on said bed, an inking cylinder rotatably held between and on said extensions, a driving element supported on said extensions, a reduction gearing train operably connecting said driving element with said cylinder, distributing rollers movably engaging the periphery of said cylinder, a vibrator roller movably engaging said distributing rollers, an inking mechanism including a roller for supplying ink to said vibrator roller, a ductor roller movably disposed intermediate said inking roller and said vibrator roller,

and a weighted operating member connected with said ductor roller and adapted to be actuated for effecting engagement between said ductor and vibrator rollers at each operation of the press, said weight serving to restore said roller at each operation to engagement with said inking roller.

Signed at Los Angeles, Los Angeles county, State of California, this 11th day of April, 1919.

ROBERT S. PHILIP.
